S. B. Jerome
Inventor.

S. B. Jerome, of New Haven, Conn.

Letters Patent No. 2057. Dated May 9, 1865.

Design for a Clock Case.

The schedule referred to in these letters Patent and making part of the same.

To all whom it may concern:

Be it known that I, S. B. Jerome, of New Haven
in the County of New Haven and State of Connecticut, have invented
and designed a new clock case; and I do hereby declare, the following
to be a full, clear and exact description of the same, when taken in
connection with the accompanying drawings and the letters of ref-
erence marked thereon, and which said drawings constitute part
of this specification, and represent:

Fig. 1. a front view, and in

Fig. 2. a side view.

My design especially relates to vitrine Clock Cases.

The following is a description of the same, as illustrated in
the accompanying drawings.

The case is octagonal in form as seen in fig. 1, covered with
enamelled cloth having the appearance of leather or with leather. A
gilt ornamental moulding around the edge upon the faces, seen in
fig. 1, with a knob, or oval head at each angle seen in fig. 1 and 2,
the dial and its rim are of the common construction.

Having thus described my design to enable others to pro-
duce the same, I claim: The design for a clock case as shown and
described.

Witness:

John E. Earle, {
Rufus Langford. }
